INVENTOR

Harvey M. Throop.

UNITED STATES PATENT OFFICE.

HARVEY M. THROOP, OF BOSTON, MASSACHUSETTS.

DESIGN FOR A BADGE.

SPECIFICATION forming part of Design No. 25,500, dated May 19, 1896.

Application filed January 23, 1896. Serial No. 576,600. Term of patent 14 years.

To all whom it may concern:

Be it known that I, HARVEY M. THROOP, a subject of the Queen of Great Britain, (having declared my intention to become a citizen of the United States,) residing at Boston, in the county of Suffolk and State of Massachusetts, have invented and produced a new and original Design for a Badge, of which the following is a specification, reference being had to the accompanying drawing, in which the figure represents a face view of my novel design.

In the badge constructed in accordance with the design illustrated in the drawing the leading features consist of the representation of an open book bearing a central square tablet, and said book and tablet rest upon a Maltese cross, which is in turn supported by a quadruple cross. Beneath said book and tablet is a triangle. Within the outer ends of the arms of the quadruple cross are placed four segments of circles. Above the two upper segments of circles is mounted an ornamental panel. To the upper edge of this panel is connected a segment and two gavels bearing above them two curved flat bars with notched flowing ends. Midway of said curved bars is mounted a keystone.

Referring more particularly to the drawing, the several features of my design are designated by letters.

A is the representation of an open book, and B the central square tablet placed thereon.

C is the Maltese cross, and D the quadruple

cross upon which said Maltese cross is supported. These two crosses are provided with narrow bands along their edges.

E is the triangle, which rests upon and overlaps the lower arms of the quadruple and Maltese crosses, as shown, with its apex pointing toward the center of the open book A.

F F represent the four segments of circles placed within the outer ends of the arms of the quadruple cross, and these segments are provided with curved narrow bands f f', between which is a flat curved surface.

G is the ornamental panel mounted above the two upper segments F, and to this panel is connected the segment H and the gavels I I, which extend inwardly and upwardly beneath the curved flat bars J J, the upper of which is shorter than the under, and each having notched flowing ends, as shown in the drawing.

K represents the keystone, which is mounted midway of the two curved bars J J.

It is to be understood that the various parts of my novel design are provided with suitable ornamental chasing and such words, letters, figures, or similar features as may be desired.

What I claim is—

The design for a badge as herein shown and described.

HARVEY M. THROOP.
